Jay W. Powers

UNITED STATES PATENT OFFICE.

JAY W. POWERS, OF MINNEAPOLIS, MINNESOTA, ASSIGNOR TO THE POWER DEVELOPING COMPANY, OF MINNESOTA.

STEAM-ENGINE.

SPECIFICATION forming part of Letters Patent No. 624,536, dated May 9, 1899.

Application filed June 5, 1897. Serial No. 639,613. (No model.)

To all whom it may concern:

Be it known that I, JAY W. POWERS, a citizen of the United States, residing at Minneapolis, in the county of Hennepin and State 5 of Minnesota, have invented a new and useful Improvement in Steam-Engines, of which the following is a full, clear, and exact description, reference being had to the accompanying drawings, which form a part of this specification.

My invention relates to a class of engines, wherein a piston is driven continuously in one direction, known as "rotary" engines; and the purpose of my invention is the production of a rotary engine wherein the steam 15 may be used expansively.

To this end my invention consists of a shaft which is rigidly affixed to an eccentric piston, said eccentric piston revolving within an elliptical chamber the minor diameter of which is equal to the diameter of the said eccentric piston and the major diameter of which is equal to twice the "throw" of the said eccentric piston, the said elliptical chamber being 25 inclosed by a case the parallel heads of which form the covers of the said elliptical chamber and provide bearings for the said shaft, all of which is herein shown and hereinafter described.

30 In the drawings, Figure 1 is a side elevation of my improved engine; Fig. 2, an end elevation thereof; Fig. 3, a vertical longitudinal section, and Fig. 4 a vertical cross-section.

Similar letters refer to similar parts throughout the several views.

The shaft A is not unlike those of other engines, and needs no description in detail. The rotary piston B consists of a short cylinder with parallel ends pierced off its center and 40 rigidly affixed to a shaft A, thus making it an eccentric. Its parallel ends are pierced to form the steam-ports *a* and *b*, which ports terminate in its opposite circumferential sides. The inner case C is suspended from 45 the pivot *c*. It consists of a shaft portion *d*, the pivot portion *c*, and the head portion *e*, having therein the elliptical chamber *f*. The depth of the elliptical chamber *f* is equal to 50 the length of the eccentric piston B, the width thereof equal to the diameter of the eccentric piston B, and the length thereof equal to twice

the throw of the eccentric piston B. This is an important feature of my invention, for upon the relative proportion of these parts depends the operation of my engine. Spring- 55 packing *g* may be employed to render the parts steam-tight; but I do not wish to confine myself to any particular form of packing. The outer case D constitutes the body or frame of my engine and may be of any desired form. 60 It should be fashioned with a base or foot, by means of which it may be secured to its foundation or support. Its depth is equal to that of the inner case C, and its width sufficient to allow the inner case C to oscillate therein 65 without contacting at its sides, and its height sufficient to allow the inner case C to oscillate therein without contacting at its bottom. The parallel heads E and E' cover the sides of the outer case D, the inner case C, and the ends 70 of the eccentric piston B. They are provided with the boxes or bearings *h*, within which the shaft A revolves, with the steam-pockets *i* and *j*, and with the ducts *k* and *l*, leading to and from the pockets *i* and *j*. A supply-pipe 75 *m* communicates with the duct *k*, and an exhaust-pipe *n* communicates with the duct *l*.

The steam-pockets *i* and *j* are annular grooves surrounding the shaft A.

The operation of my engine is as follows: 80 Live steam, being admitted through the supply-pipe *m*, flows through the duct *k* and the annular pocket *i* of the head E, through the port *a* of the rotary piston B, enters the elliptical chamber *f* of the inner case C, expands 85 therein, and drives the rotary piston B in the direction indicated by the arrow to the bottom of the elliptical chamber *f*. While the rotary piston B is thus being impelled by the live steam in the upper end of the elliptical chamber *f* the exhaust-steam in its lower end escapes through the port *b* of the rotary piston B, the annular pocket *j* and the duct *l* of the head E', and the exhaust-pipe *n*. It 90 will be seen that the rotation of the piston B 95 oscillates the inner case C, thereby holding the opposite sides of the elliptical chamber *f* in constant contact therewith, and that in its rotations it alternately enters, fills, and recedes from opposite ends of the said elliptical 100 chamber *f*, thereby forming at each revolution two crescent-shaped pockets *o* and *o'*, wherein

the steam exerts its force from the elliptical wall and against the rotary piston.

Having thus described my invention, what I claim as new, and desire to secure by Letters 5 Patent, is—

In a steam-engine, the combination of an outer case; an oscillating case suspended therein; an elliptical chamber within the said oscillating case; a cylindrical piston rotating to within said elliptical chamber; said piston being eccentrically mounted upon a shaft; said

shaft being supported by, and revolving in the heads of the said stationary case; said heads having steam pockets, ports and passages adapted to convey live steam to, and 15 exhaust-steam from the said elliptical chamber, substantially as shown and described.

JAY W. POWERS.

In presence of—

W. M. TAPPAN,
HENRY M. FARNAM.
